UNITED STATES PATENT OFFICE.

THOMAS LUND, OF BEVERLY, MASSACHUSETTS, ASSIGNOR TO UNITED EXPEDITE FINISHING COMPANY, OF PORTLAND, MAINE, A CORPORATION OF MAINE.

HEEL-BURNISHING MACHINE.

1,412,085.

Specification of Letters Patent. Patented Apr. 11, 1922.

Application filed March 27, 1917. Serial No. 157,799.

To all whom it may concern:

Be it known that I, THOMAS LUND, a citizen of the United States, residing at Beverly, in the county of Essex and State 5 of Massachusetts, have invented certain Improvements in Heel-Burnishing Machines, of which the following description, in connection with the accompanying drawings, is a specification, like reference characters on 10 the drawings indicating like parts in the several figures.

This invention relates to a heel burnishing machine and more particularly to mechanism for guiding a shoe relatively to the 15 burnishing tool.

A typical heel burnishing machine embodying a rotary heel burnishing tool is illustrated in the patent to Pease No. 743,988. In machines of that type, the rotary burnishing tool is provided with a circumferential work surface having a contour conforming with the cross-sectional contour of the heel to be burnished. A tread rest is usually provided against which the top lift 20 of the heel is rested as the latter is applied to the tool and this rest may be fixed in different positions. Such arrangements, however, take no account of the fact that in certain types of heels there is a material 25 difference in the height of the heel at its front and back with the result that if the tread rest is properly adjusted to enable the tool to be applied throughout the height of the heel at its back, it will be applied to 30 a portion of the upper of the shoe near the front of the heel. On the other hand, if the tread rest is so adjusted that it is in proper position for the height of the front 35 of the heel, obviously it will not permit the whole of the heel to be waxed or burnished.

In order to overcome this difficulty, I have devised novel mechanism for a machine of the type described comprising means for positioning a shoe to hold the rand crease 45 edge of the heel opposite to one edge of the burnishing tool as the heel is turned in being presented to the tool. This is preferably accomplished by means of a relatively fixed rand crease guide plate mounted adjacent one edge of the circumferential work 50 surface of the tool and forming a fulcrum about which the shoe may be rocked on an axis substantially tangential to the rand crease as the different portions of the contour surfaces of the heels are presented to

the finishing tool. The mechanism, which I have devised, also includes means movable transversely of the tool and automatically maintained in engagement with the tread of the heel to steady it. Such a mechanism 60 provides for variations in the height of various parts of the heel while insuring that the upper is fully protected and the heel firmly supported during its application to the burnishing tool. Evidently the rand 65 crease guide may be used independently of the tread rest.

For a fuller understanding of my invention, reference may be had to the following specification taken in connection with the 70 accompanying drawings in which,—

Fig. 1 is a perspective view of one embodiment of my invention;

Fig. 2 is a plan view of a portion thereof;

Fig. 3 is an end view of the rand crease 75 guide; and

Fig. 4 is a fragmentary view showing a heel in two positions.

Machines of this type comprise a supporting column 10, on which is mounted a shaft 80 carrying a rotary burnishing tool 12 which is driven by means of suitable gears 14. A wax spreading brush 16 insures an even spreading of the wax over the work surface of the tool and is moved relatively thereto 85 in any suitable manner, for example, in the manner shown in the above-mentioned patent. Adjacent one end of the circumferential work surface of the tool 12 is means for supporting a shoe at a point remote from the top lift of the heel in the 90 form of a rand crease guide 20 comprising a thin plate having a curved edge which corresponds substantially to the curvature of the work surface of the tool in the active 95 portion thereof. This guide plate may conveniently be provided with a flat integral lug 22 which engages a corresponding groove 24 in a supporting bracket 26. The bracket 26 is adjustably bolted to a rod 30 100 carried upon the frame of the machine. The guide 20 is held upon the bracket 26 by means of a bolt 32 and wing-nut 34 and a slot 35 in the bracket 26 allows for movement of the bolt 32 and the rand guide 20 105 transversely of the bracket. It will be seen from Fig. 3 that the guide 20 is suitably recessed to prevent interference with the end of the burnishing tool shaft as the former is adjusted on the bracket 26.

A tread rest 36 is provided which may conveniently be of the form illustrated in the patent to Pease No. 1,197,850. This tread rest is mounted upon a slide 38 by means of a bolt 40 and is angularly adjustable with relation to the work surface of the burnishing tool in the manner illustrated in the latter patent. The slide 38 is dove-tailed to a bracket 42 on the machine frame and is provided with a depending lug 44 carrying a bolt 46 having a stop nut 48. This nut co-operates with a lug 50 upon the bracket 42 to adjust the normal position of the tread rest and a spring 52 extends circles the bolt 46 and is interposed between the lugs 44 and 50 so that it urges the tread rest toward the guide 20.

The operator will apply a shoe to the burnishing tool by pushing the tread of the heel against the tread rest 36 until he can locate the rand guide 20 in the rand crease of the shoe. The resilient mounting of the tread rest enables it to accommodate itself to variations in the height of the various parts of a heel, as shown in Fig. 4, so that the burnishing action is applied to all parts of the surface thereof. At the same time the upper is fully protected by reason of the action of the rand crease guide in definitely locating the shoe relatively to the burnishing tool.

Inasmuch as there is relatively little difference in the dimensions of the small ends of different burnishing tools, the curvature of the edge of the guide 20 will always be similar to that of the tool. Besides this, the guide may be adjusted longitudinally along the rod 30 and transversely in the slot 35 as may be desired.

Having thus described my invention, what I claim as new and desire to secure by Letters Patent of the United States is:—

1. A rotatable burnishing tool provided with a circumferential work surface to treat a shoe heel throughout its height and a thin flat guide plate fixed transversely to the axis of rotation of said tool and arranged to form a guide to enter the rand crease of a shoe and forming a fulcrum about which the shoe may be rocked on an axis substantially tangential to the rand crease to present the different parts of its heel surface to the burnishing tool.

2. In a burnishing machine, a rotatable burnishing tool provided with a circumferential work surface arranged to treat a shoe heel throughout its height, a thin guide plate adjacent to one edge of said work surface and substantially at right angles to the axis of rotation, said plate having its edge arranged to enter the rand crease of a shoe operated upon, a supporting bracket extending in proximity to the end of the tool, and means for adjustably securing the plate upon the bracket, the edge of said plate be-

ing arranged to form a fulcrum about which the shoe may be rocked to bring the different parts of its heel surface into burnishing position.

3. In a burnishing machine, a rotatable burnishing tool provided with a circumferential work surface, a thin flat guide plate adjacent to one edge of said work surface and substantially at right angles to the axis of rotation, said plate having its edge arranged to enter the rand crease of a shoe operated upon and forming a fulcrum about which the shoe may be rocked to bring the different parts of the surface of its heel into contact with the burnishing tool, a supporting bracket for the guide plate extending in proximity to the end of the tool, and means arranged for varying the position of the bracket to move the plate toward and from the tool.

4. In a burnishing machine, a rotatable burnishing tool provided with a circumferential work surface, a thin flat guide plate adjacent to one edge of said work surface and substantially at right angles to the axis of rotation, said plate having its edge arranged to enter the rand crease of a shoe operated upon and forming a fulcrum about which the shoe may be rocked to bring the different parts of the surface of its heel into contact with the burnishing tool, a supporting bracket for the guide plate extending in proximity to the end of the tool, means arranged for varying the position of the bracket to move the plate toward and from the tool, and means for adjustably securing the plate upon the bracket.

5. In a burnishing machine, a rotary burnishing tool, a bracket extending in proximity to one extremity of the tool and being provided with a depression, and a flat guide plate adjacent to the tool and having a lug movable in the bracket depression to permit adjustment of the plate transversely of the tool, and means for fixing the plate in its adjusted position.

6. In a burnishing machine, a frame, a burnishing tool rotatable therein, a bracket adjustably mounted upon the frame and having at the end of the tool a depression, and a flat guide plate provided with a lug movable in the depression, the edge of said guide plate forming a fulcrum to enter the rand crease of a shoe and about which the shoe may be rocked to bring the different parts of the surface of its heel into engagement with the burnishing tool.

7. In a burnishing machine, a rotatable horizontal spindle, a burnishing tool fixed thereto, a slide arranged to move yieldably parallel to the spindle, and a tread rest arranged for adjustment upon the slide about a substantially vertical axis.

8. In a burnishing machine, a rotatable burnishing tool provided with a circumfer-

ential work surface, a thin flat guide plate adjacent to one edge of said work surface substantially at right angles to the axis of rotation and having its edge arranged to enter the rand crease of a shoe operated upon, a tread rest yieldably mounted for movement toward and from the guide plate,

and means arranged to permit the angle of the tread rest with respect to the guide plate to be varied.

In testimony whereof I have signed my name to this specification.

THOMAS LUND.
